LADDER CONSTRUCTION

Herman H. Gumz, Newark, N. J.

Application November 10, 1943, Serial No. 509,665

2 Claims. (Cl. 228—58)

This invention relates to means for constructing a ladder.

It is the principal object of my invention to provide a round or rung structure with which a ladder may be quickly built or manufactured at extremely low cost, at the same time attaining a ladder which is much stronger than ladders of the usual construction where holes are bored through the side members to receive the rungs.

My invention will be clearly understood by reference to the annexed drawing wherein:

Fig. 1 is a view of one of the side members of a ladder having one form of rung attachment applied thereto.

Figure 2 is a top view of the structure shown in Figure 1.

Figure 3 is a modified form of construction as applied to the opposite side member of a ladder.

Figure 4 is a view of the attachment used in Figure 3 looking from right to left on a reduced scale.

Figure 5 shows a further modified form of construction.

In the different views wherein like numbers refer to corresponding parts, 1 is the rung or round of a ladder (Webster's International Dictionary defines the rung as the round of a ladder) which is a tube made of thin metal either of the butted, welded or seamless type. Also, the outer periphery of the tube may be provided, directly or indirectly, with a friction surface. To the opposite ends of the tube is welded, as at 2, an attachment 3 normally in the form of a metal plate having its opposite ends 4 and 5 extending, before bending, at right angles to the axis of the tube 1, and these ends are bent over as indicated in Figures 1 and 2 to engage parts of a ladder side member 6, and are fastened thereto as by one or more screws or nails 7. In some cases, the extensions 4 and 5 need not be bent over but may extend along the side of the ladder member 6 as indicated by the dotted line 8.

As an alternative arrangement, the attachment 3 may have its extending ends bent at angles as indicated in Figure 4 to form lips 9 and 10, the lip 9 engaging one edge, for example the front edge, of the side member 11 of the ladder,

while the other lip engages the opposite or back edge of the member 11. The fitting 3 in this case is provided with suitable holes for receiving screws or nails as in Figures 1 and 2.

In Figure 5 the extending ends of the fitting 3 are adapted to bent on an arc around a circular side member 12 which may be flattened off along one side or at places corresponding to the position of the rungs in order to receive the surface of the flat plate 3. Nails or screws may be used for fastening the parts 4 and 5 to the member 12.

The rung structure as described may be made in large quantities and sold to a ladder manufacturer or to the user of a ladder who may readily construct his own ladder; and, as heretofore pointed out, since the side members of the ladder do not have to be bored out for the rungs, a much stronger ladder can be made as the metal attachment pieces 3 add materially to the strength of the ladder, especially in the form shown in Figures 2 and 4.

What I claim is:

1. A ladder rung as set forth in claim 2, further defined in that the plate ends are bent on diagonals so that one bent end may engage one edge of the ladder side member, while the other bent end may engage the opposite edge, the portions of the side member engaged by said bent ends extending a considerable distance from the axis of the rung.

2. For use in building strong work ladders having single side members, a rung composed of a stiff steel tube having flat metal plates securely welded, one at each end of the tube, the plates extending a considerable distance in two opposite directions beyond the tube, whereby a relatively large area of the same side of the side member may be engaged by the ends when straight, or the extending ends of each plate may be bent over or around opposite portions of one of the single side ladder members for substantial distances, and holes in said ends for use in fastening them to their respective side member.

HERMAN H. GUMZ.
